UNITED STATES PATENT OFFICE.

JOHN N. BROOKS, OF NORTH JAVA, NEW YORK.

BRIDLE-BIT.

SPECIFICATION forming part of Letters Patent No. 243,684, dated July 5, 1881.

Application filed February 11, 1881. (No model.)

To all whom it may concern:

Be it known that I, JOHN N. BROOKS, a citizen of the United States, residing in North Java, in the county of Wyoming and State of New York, have invented certain new and useful Improvements in Bridle-Bits, of which the following is a specification.

The object of my invention is to produce a device that can be used either as a hard or mild bit; and it consists of a reversible bit and guard, having on one side of the bit a smooth surface, forming a mild or easy bit, and on the opposite side a surface of peculiar shape, forming a hard bit, the guards or side pieces being also adapted to be reversed, so that the several straps may be used in their proper places when either the hard or soft bit is used, as will be more clearly hereinafter shown by reference to the drawings, in which—

Figure 1 is a face view of the hard bit and an edge view of the guards. Fig. 2 is a similar view, showing the mild or soft bit. Fig. 3 represents a modification showing a jointed bit. Fig. 4 is a section through line X X, Fig. 1; and Fig. 5 is an enlarged view of a portion of a bit and guard in section, showing the manner of connecting or fastening the bit to the guards.

A represents the bit; *a a'*, two longitudinal grooves arranged on one side of the same. (See Fig. 1.) They are angular in cross-section, so as to present two sharp edges, *b b'*, as in Fig. 4. One of the grooves, *a*, is arranged above a central line, *z z*, and the other, *a'*, below it. This side is what may be called a "hard bit." It will be noticed that the grooves are arranged so that while the part *r*, having the edge *b*, forming a part of the groove *a*, projects forward in the direction of the arrow, (see Fig. 4,) the same part of the groove *a'* projects in the opposite direction. The opposite side, *c*, (see Fig. 2,) of the bit is smooth, so as to form a mild or easy bit. B represents a hole by which the usual chain and ball for preventing the horse from putting out his tongue may be attached, if desired.

The bit is rigidly fastened to the guards *C C'* by means of two prongs or projections, *d*, (shown by dotted lines in Fig. 5,) arranged on each end of the bit, and passed through holes

in the guards, (shown by dotted lines *e e* in Fig. 4,) which prongs are afterward bent over or riveted, as shown at *f* in Fig. 5. The guards *C C'* are each provided with holes for receiving the several straps. *D* and *D'* are to hold the lines by.

The holes *E E'* are for the headstall-strap. *F F'* are used both for the check-reins and tie or hitching strap, according to the position of the guards, the lower ones always being used for the hitching-strap and the upper ones for the check-reins—*i.e.*, when the hard bit is used *F F'* would be the upper holes, and the check-reins would then be in one of the said holes and the tie-strap in *G* or *G'*; but if the bit is reversed, so as to bring the easy bit into use, the holes *G G'* would be the upper ones, in which case the check-reins would be removed from the holes *F* or *F'* to the holes *G* or *G'*, which would then be upper holes, and the tie-strap would be removed from *G* or *G'* to *F* or *F'*. The straps in the other holes are also likewise changed when the bit is reversed.

If desired, the bit may be made in two parts and connected together in the center by a joint, *J J'*, (see Fig. 3,) in the usual manner, so as to form a jointed bit. By this arrangement the advantages of a hard bit and an easy bit are combined in one. The arrangement of the holes in the guards for the different straps adapts it to be easily reversed, so that either bit may be used.

I claim as my invention—

1. A bridle-bit, *A*, one side of which is smooth and the other provided with the sharp angles *b b'*, in combination with the guards *C C'*, adapted to be reversed, so as to be used either as a hard or mild bit, as described.

2. A bridle-bit consisting of the reversible guards *C C'*, provided with the openings *D D'*, *F F'*, *E E'*, and *G G'*, and a reversible bit, *A*, having a smooth face, *c*, on one side, and a face having the sharp angles *b b'* on the opposite side, for the purposes specified.

JOHN N. BROOKS.
